UNITED STATES PATENT OFFICE.

PHILIP J. ROWLAND AND CHARLES J. SCANLAN, JR., OF SAN FRANCISCO, CALIFORNIA.

26 GAME.

Application filed January 5, 1926. Serial No. 79,297.

This invention relates to improvements in game apparatus, and more particularly to an apparatus of the coin or token controlled type designed for the playing of the well known dice game (26).

The invention has for its objects to provide mechanism releasable on the depositing of a coin or token for operation for a predetermined number of times, after which the same is precluded from operation until another coin or token is deposited; to provide a mechanism wherein locking means are provided for preventing the operation of the apparatus until such time as a coin or token is deposited; to provide an apparatus capable of releasing on the depositing of coins or tokens of different value or denomination and to provide means for recording within the apparatus the number of coins or tokens of different value or denomination deposited at any one time for releasing the apparatus for its initial operation of its predetermined number of times.

Further objects are to provide a novel form of operating means for the table on which rest the game pieces, and to provide means for delivering the operating coins or tokens exteriorly of the apparatus after the same have completed their function.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawings, wherein—

Fig. 1 is a view in plan of the preferred embodiment of our invention, illustrating particularly the casing; the rotating table with the playing pieces; coin or token slots, and some of the indicating mechanism.

Fig. 2 is a sectional view on line 2—2 of Fig. 1, in the direction of the arrows.

Fig. 3 is a sectional view on line 3—3 of Fig. 2.

Fig. 4 is a longitudinal sectional view taken on line 4—4 of Fig. 1. 55

Fig. 5 is a longitudinal central sectional view taken on line 5—5, Fig. 1, viewed in the direction of the arrows.

Fig. 6 is a transverse sectional view taken on line 6—6 of Fig. 4, viewed in the direction 60 of the arrows.

Fig. 7 is a transverse horizontal sectional view of the apparatus, illustrating particularly the operating means for recording mechanism. 65

Fig. 8 is a vertical transverse sectional view taken on line 8—8 of Fig. 4.

Fig. 9 is a transverse sectional view on line 9—9 of Fig. 8, with the locking bar in lowered position. 70

Fig. 10 is a similar view of the locking bar in raised position.

Fig. 11 is a transverse sectional view on line 11—11 of Fig. 8, with the locking bar in raised position. 75

Fig. 12 is a similar view with the locking bar in lowered position.

Fig. 13 is a transverse sectional view on line 11—11 of Fig. 8, with the mechanism pivoted from its normal position. 80

Fig. 14 is a similar view with the mechanism in its normal position.

Fig. 15 is a view in fragmentary elevation of the structure illustrated in Fig. 16, taken on line 15—15 of Fig. 16. 85

Fig. 16 is a view taken on line 16—16 of Fig. 15.

Fig. 17 is a view in perspective of one of the hammer actuated push bars.

Fig. 18 is a view in detail section of the pivoted bar and its limiting screw taken on line 18—18 of Fig. 7. 90

Fig. 19 is a transverse sectional view of the recording means taken on line 19—19 of Fig. 20. 95

Fig. 20 is a view in side elevation of the recording means taken on line 20—20 of Fig. 19, viewed in the direction of the arrows. 100

Fig. 21 is a view in detail top plan of the recording tape illustrating the impressions.

made by the printing type and the punch point depressions therein.

Fig. 22 is a view in detail top plan of the game table, illustrating the pawl for actuating the cam end of the table operating lever.

Fig. 23 is a bottom plan view of the mechanism illustrated in Fig. 22.

Fig. 24 is a view in side elevation of the table, illustrating particularly the bearing mounting for its shaft.

Fig. 25 is a fragmentary end view of the cam end of the table operating lever.

Fig. 26 is a diagrammatic view of the cam end of the table operating lever and its associated pawl, taken on line 26-26 of Fig. 25.

Fig. 27 is a view in detail of the mechanism for retarding the return movement of the tiltable coin slot frame.

Fig. 28 is a view in fragmentary elevation of the cam wheel and its associated mechanism for precluding further operation of the table, after the same has been operated 25 a given number of times after the depositing of a controlling coin or token, and also the release mechanism for releasing the controlling pawl associated therewith.

Fig. 29 is a view in detail plan of the mechanism for securing the bottom and case together.

In the drawings, the numerals 1 indicate the side walls of a cabinet; 2 the bottom and 3 the top; the side and top walls being detachably secured together in any suitable manner to constitute a unit structure. The lower edge of the side walls are received within the annular upstanding flange 4 of the bottom 2, and said side walls 1 carry on their inner 40 face cam lugs 5 for engagement by pivoted cams 6 controlled by operating rods 7; the cams and rods being associated with the upper surface of the bottom wall 2.

In its center the top wall 3 is provided 45 with an opening normally closed by a glass or other transparent dome 8, and said opening has a bevelled peripheral edge 9, as in Fig. 5, said bevelled edge carrying at spaced points projections 10—Fig. 1.

Carried on the upper end of a vertical shaft 11 and rotatable at its lower end in a supporting bracket 12, Fig. 24, is a circular game table or board 13, on the upper surface of which are adapted to rest a plurality of 55 game pieces 14, the same being illustrated in the form of dice, and preferably ten in number, as in Fig. 1.

In its center, the table 13 carries an inverted cup 15 affording a raised portion. 60 The shaft 11 carries a ratchet 16, Figs. 5, 22, 23 and 24, and with the same is adapted to cooperate a pivoted pawl 17, the free end of which is projected toward the ratchet by a tension spring 18. The pawl and spring 65 are mounted on one end of a substantially S-

shaped lever 19 pivoted to the plate 20 carrying bracket 12, as at 21, and the opposite end of the lever projects beyond the periphery of the game board or table 13 and is formed with the oblique faces 22 and 23. 70

A spring 24' connected at one end with the lever 19 maintains the lever in its normal position, as in Figs. 22 and 23, and imparts movement to the lever to cause the rotation 75 of the board or table 13.

The means directly associated with the end of the lever 19 for operation to move the same in the direction of the arrow Figs. 22 and 23 to permit the spring 24' to rapidly return the lever and rotate the game board 80 or table, consists of a pawl 24 pivoted to a stud 25 to swing on an axis parallel with the direction of movement of the lever 19, and the stud is in turn carried at one end of a bar 26 fulcrumed at its opposite ends, as at 85 27, Figs. 5 and 8, to the sides of a sub-frame 28 within the cabinet, previously described. The fulcrum point 27 is so disposed as to enable the stud 25 to swing at right angles to the path of movement of the free end of 90 the lever 19, as illustrated in Figs. 22 and 26.

It will be observed that an upward movement of the pawl 24 in the direction of the arrow Fig. 26, will ride on the face 22 and 95 swing the free end of lever 19 in the direction of the arrow A.

On the pawl reaching the upper edge of the face 22, the spring 24' will rapidly move the lever 19 to its normal position, causing 100 the pawl 17 to engage the ratchet 16 and rotate the table. On the downward movement of the pawl 24, the same will pivot on its stud 25 in its riding movement downwardly with the face 23, Fig. 26.

A bar 26 extends transversely of the cabinet between the side members of the sub-frame 28 and is provided with a plurality of vertically disposed open ended coin or token receiving slots 29, each slot being preferably of a size to accommodate a coin of a different denomination. 110

The cabinet top wall 3 is provided at points over the slots with coin or token insertion slots 30 adapted to align with the slots 29 115 when the latter are in vertically disposed position.

Arranged horizontally beneath the bar 26 is a transversely slotted coin or token supporting bar 33 on which rests the lower edges 120 of the coins or tokens as the same are received within the respective slots 29.

Slidably mounted on one face of the bar 26 is a hammer contacting bar 31, Figs. 6 to 10 inclusive, adapted as hereinafter described for raising to admit of a hammer to coact with a deposited coin or token and pivot the bar, or for lowering to admit the hammer striking the same and pivot the bar. The hammer contacting bar 31 freely 130

slides between one face of the bar 26 and guide brackets 32 and in its lowermost position fails to contact with the coin supporting bar 33, which is radially slotted as at 34 and admits the movement of the hammers, hereinafter described, thereinto.

The hammer contacting bar 31 controls the operation of the table, in that the same is actuated to raise on the completion of the 10 predetermined successive rotations of the table and thus be removed from engagement by the hammer until such time as the bar is again lowered. When the bar is raised, the hammer passes beneath the same and only 15 pivots the bar 26 on engaging a deposited coin or token in one of the slots 29, after which initial operation the hammer contacting bar 31 lowers for engagement by the successive operation of the hammers.

20 The mechanism for carrying out these operations is constructed and arranged in the following manner:—On a shaft 34 is mounted a ratchet wheel 35 and disk 36, the periphery of the latter at one point being recessed at 37, Figs. 5 and 28. Riding on the periphery of the disk 36 is a roller 38 on the end of a lever 39, the roller being held in contact with the periphery of the disk by a spring 40. The free end of the lever 39 engages with an arm 41 extended laterally from a shaft 42 disposed beneath the bar 33. The shaft 42 carries at spaced points arms 43 which are pivotally connected at their free ends with the lower ends of vertically 35 reciprocating rods 44 slidable through openings in the bar 33 and each provided with an enlarged head 45 for contacting with the under edge of the bar 31 at its ends for raising and lowering the same.

40 It will be observed that when the roller 38 is riding on the periphery of disk 36, the bar 31 is in its lowered position, and when the roller is received in the recess 37, the bar 31 is raised to permit the hammers, when actuated, to pass beneath the same.

The ratchet wheel 35 and disk 36, which are held in their rotated position by the pawl 46, are rotated in unison in a step by step movement in the direction of the arrow—50 Fig. 5, on each operation of the hammers, hereinafter described. The mechanism for accomplishing this rotation consisting of a reciprocating rod 47, Fig. 28, guided by a pin 48 operating in a slot 49 therein, engages 55 at its lower curved end 50 with the teeth of the ratchet 35. The upper end of the rod 47 is bevelled at 51 to be engaged by the corresponding surface on the underface of one end of bar 26, thus on the swinging of 60 the bar 26, the rod 47 raised by the spring 52, engages at its lower end 50 a successive depression in the ratchet 35, and on the downward movement of the bar 26, assisted by the spring 53, the ratchet and disk are ad-

vanced a predetermined distance in the direction of the arrow—Figs. 5 and 28.

From the above description, it will be observed that on each complete revolution of the disk 36 and ratchet 35 from a point where the roller 38 registers with the depression 37, the hammer, hereinafter described, operates the bar 26 by contacting with the hammer contacting bar 31, but on the roller 38 dropping in the depression 37, a separate medium in the form of a controlling coin or token must be deposited within one of the slots 29 to form an abutment for the hammer, hereinafter described.

Disposed transversely of the sub-frame 28, beneath the bar 26, and fulcrumed at its ends to pivot within the frame, is a hammer supporting bar 54, upwardly from which extend a plurality of hammer bars 55, one adapted for co-operation with each of the slots 29 in the bar 26. The hammer bars are mounted to swing at right angles to the bar 26, and the upper end of each is provided with an extension 56 and an upstanding abutment wall 57. The upper end of each hammer, in its movement toward the bar 26, passes through one of the transverse slots 58 in the coin supporting bar 33.

When the roller 38 is received in the depression 37, of the disk 36, Fig. 28, the bar 31 is raised and the hammer bars 55 are free to pass beneath the bar 26, then tilt the same unless there be a coin or token dropped within one of the slots 29—Fig. 14. If the latter is the case, the forward end 56 of the hammer bar passing beneath said slot contacts with the inner face of the coin or token which is resting on the upper surface of the bar 33, binds the same within the slot 29, Fig. 13, and removes the lower edge of the coin or token from its support 33; the coin or token thus affording an abutment for the hammer, and the movement of the hammer causing a tilting or oscillation of the bar 26, which, as above described, actuates the member 47 to rotate the ratchet 35 a notch.

The coin which has served as an actuating coin drops on the return movement of its coating hammer bar 55 to normal position, into the chute or trough 58, which conveys it to the pocket 59 for removal by the attendant at his will.

Referring to Fig. 4—60 indicates an operating lever extended through a slot in the cabinet wall 1, and at its inner end is fulcrumed to pivot at 62. The lever is normally held upwardly by a spring 63 and near its point of fulcrum carries a cam portion 64 which coacts with a roller 65 extended from one side of an arm 66 projecting from the bar 54.

120 Thus it will be observed that a downward movement of the lever 60 will, through the roller 65, cause a forward movement of the

hammer bars 55. A spring 67 hooked at one end to the sub-frame 28 and at its opposite end to an arm 68 extending laterally from the member 54, Fig. 28, normally maintains the member 54 in the full line position, indicated in Fig. 27, and to retard the movement of the member 54 from dotted line position to full line position, Fig. 27, a pawl 69 is provided which engages the teeth or serrations 70 on the free end of the arm 66.

To momentarily hold the bar 26 in its operated position, full line, Fig. 13, and dotted line, Fig. 27, a latch 71, spring held, as at 72, is provided for engaging the hooked end of an arm 73 extending at right angles from the bar 26. The latch 71 is released by the action of the arm 66 in its upward movement to normal position, striking the curved extension 74 of the latch 71.

20 The means for indicating the token or coin value and recording the number of respective coins or tokens received in any given slot of the machine, is constructed and operates in the following manner:—

25 It will be apparent that this mechanism only operates at such time as a coin or token is deposited within the apparatus, enabling the initial rotation of the table and the removal of the roller 38 from the depression 37.

Associated with each slot 27 and longitudinally slideable with their corresponding ends disposed parallel with the top of the surface of plate 33, and to contact with one face of the lower edge of a coin on the same being deposited within the slot 27 and the coin utilized as an operating medium, as previously described, are a plurality of slide bars 75, Figs. 5 and 7. With each of these 35 slide bars is connected as at 76 an auxiliary slide bar 77, the corresponding ends of the respective bars being pivotally connected to respective levers 78, the latter being pivotally connected at their lower ends through 40 links 79 with the respective arms 80 of well known types of indicating mechanisms 81, which are positioned in rear of openings 82 in the wall of the cabinet. Springs 83 normally maintain the ratchets 75 in their normal position, illustrated in Figs. 5 and 7. Corresponding ends of rods 77 are bent laterally and downwardly, and on its end each carries a pivoted pawl 84. The free end of each pawl 84 is adapted to coact with the angle portion 85 of a type bar 86 pivoted to a support as at 87, and each type bar at its end is provided with a character 88 overlying a bed plate or platen 89. A spring 90, Figs. 5 and 7 coacts with each type bar to 45 depress the same to cause an imprint of the type character, after the type bar has been raised in a hereinafter described manner and suddenly released.

It will be observed that on the actuation 50 of any one of the members 75, the action of

the pawl 84 will cause its associated type bar and character to be raised against the tension of spring 90, and on pressure on the actuating hammer bar 55 being released, the coin or token will drop into the chute 58 and enable the spring 83 to reciprocate the rod 75, after which time the spring 90 will depress the type character.

Over the platen 89, Figs. 19, 20 and 21, lies an inked ribbon or printing device 91 which operates over rollers 92, and beneath said member 91 operates a strip 93 preferably of paper, the same being carried on the spool 94 and wound on the spool 95, the mechanism for this operation being constructed as follows—Figs. 6 and 7. Connected with the spool 95 is a flexible driving member 96 passing around the spool with which is associated a ratchet 97, and co-operating with this ratchet is a spring held pawl 98 on the lever 99. The lever 99 extends beneath levers 100, Figs. 20 and 21, the ends of which overlie the platen 89 at one side of the printing characters 88, and each is provided preferably with a perforating or puncturing pin 101, which are adapted for operation on the movement of the respective levers 100 to imprint characters differing from those printed by the members 88 into the sheet 93. The levers 100 are connected through links 102 with rectangular links 103, the latter being connected with arms 104 carried by transversely disposed shafts 105 journaled at their ends in the subframe 28. The rods or shafts 105 each carry an arm 106 each connected through links 107 with levers 108 preferably two in number, the ends of the levers extending through the cabinet wall 1 and terminating in finger or key pieces 109.

To indicate the number of times the selected face of the dice or playing pieces appear upwardly on the gameboard, suitable dial members 110 are rotatably mounted in bearings with a portion of their periphery visible through an opening 111 in the top wall 3 of the cabinet. The dial members are consecutively numbered, in the present instance they are 1 to 36, and while but two are illustrated, any number may be provided, one being utilized by each player in keeping his score of the selected dice numbers. Each dial member carries a ratchet 112 with which co-operates a pawl 113 on an arm 114, and each of said arms co-operates with one of the links 107 and extend between spaced pins 115 extending laterally therefrom. It will be observed that the player on depressing the key piece 109 will on each depression revolve the dial member associated with the key piece one number, and at the same time will cause the pin 101 associated with it to make an impression on the strip 93 and will also operate the lever 99 to cause the strip 93 to be advanced across the platen one step from the spool 94 to spool 95; thus there is 110 115 120 125 130

5 maintained on the strip 93 a record of the coin or token value of the coins or tokens deposited within the apparatus, and also a record of the number of times that the selected playing face of the playing piece or dice selected by any given operator is disposed upwardly on successive rotations of the table or gameboard.

10 To indicate the dice or playing piece face number selected by the respective players, there is provided for each player a hexagonal indicator 116, the periphery of which is visible through an opening 117 in the top wall 3 of the cabinet, the indicator being revolvable with a shaft 118 carried in bearings 119, the shaft mounting a thumb or finger piece 120 accessible to the operator. The periphery of the members 116 is preferably consecutively numbered from 1 to 6.

20 15 In playing the game the player selects the dice or playing piece face which is to be retained by him throughout the thirteen throws of revolutions of the table or gameboard 13 and adjusts the indicator 116 so that the selected number appears through the opening 111. A coin or token is deposited within one of the slots 30 depending on its value, and the same enters the slot 29 resting on the upper surface of the member

- determined number of operations of said manually actuated table operating means.
2. A game apparatus including a movable game table for supporting a plurality of game pieces, manually actuated table operating means, a coin controlled connection between the table and the table operating means, whereby on the depositing of a coin and the operation of the manually actuated means an initial movement is imparted to the table, means for indicating the coin value deposited, means associated with said connection and operative after said initial table movement whereby on successive operations of said manually actuated means corresponding operations are imparted to said table, and means for rendering said last mentioned means inoperative after a predetermined number of operations of said manually actuated table operating means.
3. A game apparatus including a rotatable game table for supporting a plurality of game pieces, manually actuated table operating means, a coin controlled connection between the table and the table operating means whereby on the depositing of a coin and the operation of the manually actuated means an initial movement is imparted to the table, means for receiving the coin and discharging the same exteriorly of the apparatus, after the initial operation of the table, means within the apparatus for indicating the value of the deposited coin, and means associated with said connection and operative after said initial table operation whereby on a predetermined number of successive operations of said manually actuated means corresponding operations are imparted to said table.
4. A game apparatus including a rotatable game board on which rests a plurality of game pieces, a single manually actuated board operating means, a connection between the board and board operating means and provided with a plurality of coin recesses whereby on the depositing of a coin in any of said recesses and the operation of the manually actuated means rotation is imparted to the board, means for conveying the deposited controlling coin exteriorly of the apparatus, and means for recording the value of the coins passing through said recesses.
5. A game apparatus including a rotatable game board on which rest a plurality of game playing pieces, manually actuated board operating means, a connection between the board and board operating means including in part a movable coin receiving slotted bar, hammers cooperatable with the bar slots and movable to contact with a received coin to move the bar, a gate associated with the bar and movable into the path of the hammers after the initial movement of the bar, and means for controlling the number of operative movements of the hammer after each initial movement of the bar.
6. In a game apparatus, a rotatable game board on which rest a plurality of game playing pieces, a board operating lever provided with a bevelled free end, a pawl and ratchet mechanism connection between the manually operated lever and the board operating lever including a pivoted pawl provided with a bevelled face for cooperating with the free end of the board operating lever, and a support for the pawl and for operation to move the same across the path of the lever.
7. In a game apparatus, a rotatable game board on which rest a plurality of game playing pieces for agitation by the rotation of the board, a lever for manual operation to actuate said board, a coin controlled operating connection between the lever and game board, a plurality of coin slots communicating with said mechanism, and mechanism within the apparatus for indicating the slot into which the operating coin was deposited.
8. In a game apparatus, a rotatable game board on which rest a plurality of game playing pieces for agitation by the rotation of the board, a lever for manual operation to actuate said board, a coin controlled operating connection between the lever and game board, a plurality of coin slots differing in size and mechanism within the apparatus for indicating and recording the coin values deposited into the apparatus in accordance with the slot through which they were inserted.
9. In a game apparatus including a rotatable game board on which rest a plurality of game playing pieces, a transparent cover for the board, a cabinet supporting the cover and enclosing the board, mechanism within the cabinet for operation to impart a predetermined number of independent rotations to said board, and releasable means for locking the mechanism from further operation after the determined number of operations have been imparted to said board.
10. In a game apparatus including a rotatable game board on which rest a plurality of game playing pieces, a transparent cover for the board, a cabinet supporting the cover and enclosing the board, coin releasable mechanism within the cabinet for operation to impart rotative movement to the board, a coin receiving runway for directing an operating coin into operative relation with the mechanism, and through which the operating coin is discharged after passing through the mechanism, and a handle for operation to actuate said mechanism.
11. A game apparatus including a rotatable game board on which rest a plurality of game playing pieces, a lever, a spring for operating the lever in one direction, a

cooperative pawl and ratchet connection between the lever and game board operative on the movement of the lever against the tension of the spring, and a pivoted pawl 5 operatively movable in a direction at right angles to its pivot against the lever, a stop for the pawl whereby on the operative movement of the pawl in one direction the lever

is moved against the action of the spring and on the return movement of the pawl 10 the same is caused to ride over said lever.

In testimony whereof we have signed our names to this specification.

PHILIP J. ROWLAND.

CHARLES J. SCANLAN, JR.
